JOHN A. LARKIN, OF NEW YORK, N. Y.

FILLER PIECE FOR STRUCTURAL-STEEL-FRAMEWORK FIREPROOFING

Application filed May 15, 1928. Serial No. 278,002.

This invention relates to the fireproofing of structural steel framework as applied to building construction, and has particular reference to an improvement in the mode or 5 method of fireproofing the framework by enclosing or encasing the beams, girders and columns with a cementitious or plastic coating.

In providing the elements of a structural 10 steel framework with a fireproof covering such as cement, concrete or other analogous poured plastic mixtures, it has been the general practice heretofore to fill the mixture in the space defined between the flanges and 15 webs of the elements such as the beams, girders or columns which are of the conventional H-beam, I-beam or channel shape. In view of the fact that the various municipal, 20 State or Federal regulations governing the fireproofing of structural steel framework, require the covering of the members with the fireproof material only to the extent of two inches beyond the surfaces or edges thereof, it is obvious that in addition to the waste of 25 the fireproofing material which fills in the channels defined between the flanges and webs of the members under the present methods and practices, an unnecessary amount of steel must be used to support the 30 weight of the additional fireproofing material which fills in the channels.

It is, therefore, the outstanding object of 35 the present invention to provide means for excluding the fireproofing material from the channels without detracting from its primary function of protecting the framework in event of fire.

Other objects flowing from the invention 40 reside in the provision of an improved molded fireproof covering for enclosing structural steel framework members which effects an economy in the amount of fireproofing material used, and which therefore reduces the weight of the fireproofing material employed, 45 allowing for the reduction of the quantity of steel used or the diversion of the same quantity of steel to an additional use such as the increase in the height to which the building may be erected.

50 More specifically, the invention com-

hends in combination with a molded fireproof covering for the members of a structural steel framework, which members define channels therein, of filler elements extending across the open sides of the channel 55 for excluding the fireproofing material therefrom.

The invention furthermore contemplates a filler form for use in connection with girders, beams or horizontal elements which is so 60 constructed as to permit the molded fireproofing material to form extensions engaging over the upper surfaces of the lower flanges of said members for obtaining the proper anchorage of the material thereto.

Other objects of the invention reside in the simplicity of construction and mode of use of the filler form, the economy with which it may be produced and installed and the general efficiency derived therefrom.

With the above recited and other objects in view, reference is had to the following description and accompanying drawings, in which there is exhibited one example or embodiment of the invention, while the claims 75 define the actual scope of the same.

In the drawings:

Figure 1 is a sectional plan view of a structural steel column or vertical member enclosed in the improved fireproofing material 80 constructed in accordance with the invention.

Figure 2 is a transverse vertical sectional view therethrough taken approximately on the line indicated at 2-2 in Figure 1.

Figure 3 is a vertical cross sectional view 85 through a structural steel column or beam enclosed in a fireproofing material constructed in accordance with the invention.

Figure 4 is a side elevation of a beam or girder showing the filler form installed.

Figure 5 is a perspective view of one of the filler forms used in connection with columns or other vertical members.

Referring to the drawings by characters of reference and particularly to Figures 1 and 2, A designates a column or vertical member of a structural steel framework which is of the conventional H-shape or I-shape in cross section and which includes a web B and the flanges C which define a channel or channels 100

D. The fireproof covering 10 in this instance is excluded from the spaces or channels D by means of a filler form 11 of any suitable material such as sheet metal, the filler form being provided with inwardly extending angular flanges 12 which snugly fit the inner faces of the flanges C of the column or member A. In practice, the usual forms E, illustrated in broken lines, are positioned around the column or member A in properly spaced relation thereto, while the filler form or forms 11 are positioned in place, after which the plastic mixture is poured or introduced between the forms E, the filler form 11 and exposed exterior surfaces of the column. Obviously, this excludes the mixture from the spaces or channels D, the filler form 11 remaining permanently in place. The finished covering when set extends around or encloses the structural steel framework member and effectually performs its function of fireproofing the same while eliminating the unnecessary weight as well as the waste of the fireproofing substance which ordinarily enters the channels D.

In horizontal framework members such as beams or girders designated at F which are of the conventional I-beam or channel shape type having a web G and flanges H forming a channel or channels I, the filler form 13 which is employed in this instance has its upper angularly extending and inwardly projecting flange 14 arranged to snugly fit the inner surface of the upper flange H or the girder or beam F while the lower flange 15 of the filler element is disposed at such an angle as to define between the girder or beam a space preferably wedge shaped which allows an extending anchoring toe 16 to be formed from the fireproofing material 17. This anchoring toe or key when the material sets presents an additional supporting means for the fireproofing material. In practice, in this instance the outer removable forms J are positioned around and properly spaced from the beam or girder F and the filler element or elements 13, after which the fireproofing mixture is introduced therebetween, as will be clearly understood.

From the foregoing, it will thus be seen that a method and means has been devised for excluding a fireproof covering from the channels which are defined between the web and flanges of the elements of a structural steel framework, to avoid the waste of the material and to eliminate the weight of the same which is ordinarily occasioned by the fireproofing material entering the channels under the present methods and practices.

What is claimed is:

1. The combination with a moulded fireproof covering mixture for the members of structural steel framework formed with a channel, of a filler plate insertable within the

channel for excluding the covering mixture from the channel.

2. The combination with a moulded fireproof covering enclosing structural steel framework elements having a web and flanges which define a channel therein, of means for excluding the moulded covering from the channels comprising a channel shaped filler plate inversely arranged in the channel of said member.

3. In a structural steel framework, the combination with a moulded fireproof covering for the horizontal channel shaped members of the same, of a channel shaped filler form inversely arranged in the channel of each member having a lower flange extending inwardly and downwardly at an angle whereby said filler form excludes the fireproof covering from the channel except at a point immediately above the lower flange of each member.

Signed at 1457 Broadway, New York city, in the county of New York and State of New York this 14th day of May, 1928.

JOHN A. LARKIN.
